United States Patent

Des. 241,200
Patented Aug. 31, 1976

241,200

COMBINED TOOTHBRUSH HOLDER AND MOUNTING BRACKET THEREFOR

Milton Halsted, Long Beach, Ivan A. McIntyre, Westminster, David Y. Muramatsu, Costa Mesa, and James P. Sullivan, Tustin, Calif., assignors to Chicago Specialty Manufacturing Company, Skokie, Ill.

Filed June 4, 1975, Ser. No. 583,755

Term of patent 14 years

Int. Cl. D23—02

U.S. Cl. D6—94

FIG. 1.

FIG. 2.

FIG. 3.

FIG. 4.

FIG. 5.

FIG. 1 is a perspective view of a combined toothbrush holder and mounting bracket therefor, showing our new design.

FIG. 2 is a front elevational view.

FIG. 3 is a side elevational view, the side opposite being a mirror image thereof, the toothbrush being shown in broken lines for illustrative purposes only.

FIG. 4 is a top plan view.

FIG. 5 is a bottom plan view.

We claim:

The ornamental design for a combined toothbrush holder and mounting bracket therefor, as shown and described.
